LIPSTICK HOLDER

Harry Broder, New York, N. Y.; William Felstiner, Leonard Broder, and Joseph F. Berlinger, executors of said Harry Broder, deceased, assignors to Leonard Broder, Flushing, N. Y.

Application February 12, 1946, Serial No. 647,059

8 Claims. (Cl. 206—56)

1
This invention relates to a lipstick holder of the type having a lipstick cartridge arranged to be retracted into or projected from the holder by a relative rotation of certain of the parts.

As ordinarily constructed, the lipstick holder comprises a cartridge carrier having a laterally projecting pin, an inner shell presenting a bore to accommodate said carrier and formed with a longitudinal guide slot for the carrier pin, an outer shell member formed with a helical groove to receive the carrier pin, and a base made fast to the inner shell and rotatable therewith, relatively to the outer shell, in one direction to project the lipstick cartridge outwardly from the bore for use, and in the opposite direction to retract the cartridge into the bore.

It is also customary to provide such a lipstick holder with a cover to prevent access to the lipstick of contaminating foreign matter, as well as to prevent the lipstick itself from coming in contact with and soiling other articles.

In my former Patent No. 2,351,395, issued June 13, 1944, the cover is seated upon the base in spaced relation to the outer shell whereby relative rotation of the inner and outer shells is prevented until the cover is removed. To hold the cover removably in place, the base is formed with an integral cone-shaped collar or with a series of integral bevelled lugs to make frictional contact with the inner face of the cover. This frictional contact between the cover and base is insufficient to prevent the turning of the base with reference to the cover but any such turning has no effect upon the lipstick carrier due to the clearance between the cover and the outer shell, the entire holder turning freely and idly within the cover. This characteristic is known as "free wheeling" in the trade and constitutes an important feature, since any up or down movement of the lipstick cartridge within the holder is prevented whenever the cover is in place even though the base may be inadvertently rotated with reference to the cover.

The foregoing description applies to lipstick holders of the prior art whether they be made wholly of metal or wholly of molded plastic material, or whether partly made of each. In all instances, the lipstick holders possess the disadvantage that it is difficult to manufacture the cover and the base with the degree of accuracy necessary to provide for the proper frictional engagement between them to hold the cover in place. Thus, if the internal dimension of the cover is too small, the cover either cannot be applied or, if applied, may become fractured

2
(especially if made of molded plastic material) because of the excess pressure exerted by the friction surfaces on the cover. On the other hand, if the internal dimension of the cover is too large, it will fail to make the proper contact with the friction surfaces of the base and hence will fail to stay in place when applied. Standardization of parts, which is so desirable in production manufacture, is practically impossible. **10** The defect above noted is particularly true of lipstick holders of the all-plastic type, such as shown in my prior patent above mentioned, due to the inevitable warping or distortion which takes place in curing, but it is also true of lipstick holders of the all-metal type, even if in lesser degree, due again to the inevitable warping or distortion which takes place in the metal drawing or other shaping operations because of the stresses set up in the metal. **15** Another defect with lipstick holders of the prior art goes to the form and arrangement of the outer shell with reference to the base. Ordinarily, and as shown in my prior patent aforesaid, the outer shell seats at its lower end upon the upper face of **20** the base. Unless these parts are made with the greatest accuracy, which is very difficult for the reasons above stated, the line of juncture between the parts will be very noticeable and thus give an unsightly appearance to the finished article. **25** The present invention is intended to obviate the above and other difficulties and contemplates a new form of base construction for lipstick holders which will not only cover up or conceal the line of juncture between the outer shell and **30** the base and produce a neat pleasing finish to the article, but, in addition, will function unerringly to hold the cover in place notwithstanding any warping or distortion of the parts in manufacture. To these ends, specifically, the base is made **35** up of a solid metal part and of a sheet metal part, joined together as a unitary structure. The sheet metal part presents a collar portion sufficiently spaced from the inner shell to accommodate the outer shell and rises above the lower end of the latter to conceal its line of juncture with the base. The sheet metal part is also formed in said collar portion with three sheared-out spring fingers arranged at 120° apart around the circumference of the collar and which bear against the inner face of the cover to hold it frictionally in place upon the base. In one form, the cover is of full length and rests at its lower end upon the solid part of the base; whereas in another form, the cover is of short length and rests at its lower end upon an annular bead struck up from the upper

end of the collar portion of the sheet metal part, said collar portion in this instance being made high or long enough to enclose that portion of the outer shell below the cover. In both forms, the three spring fingers act in the same way to hold the cover in place, exerting by reason of their resilience the proper degree of friction upon the cover regardless of any warping or distortion thereof within the manufacturing tolerance while permitting a free or idle rotation of the base with reference to the cover. The two part base, as thus constituted, is made fast to the inner shell by a suitable swaging operation. The exact construction and operation of the parts will best be understood from the detailed description to follow, it being intended here merely to give a brief and general outline of the new construction.

Referring to the drawings:

Fig. 1 is an elevation of a lipstick holder embodying the present improvements;

Fig. 2 is a vertical section taken on the line 2—2 of Fig. 1;

Fig. 3 is a horizontal section taken on the line 3—3 of Fig. 2;

Fig. 4 is an exploded view of the parts comprising the combined inner shell and base;

Fig. 5 is a vertical section taken through the parts shown in Fig. 4 when assembled, but prior to being fastened together;

Fig. 6 is a horizontal section taken on the line 6—6 of Fig. 5;

Fig. 7 is a view similar to Fig. 5, but showing the parts fastened together by a swaging operation;

Fig. 8 is a horizontal section taken on the line 8—8 of Fig. 7;

Fig. 9 is an elevation of the combined inner shell and base shown in Fig. 7 illustrating the inner shell as spread apart to permit the insertion of the cartridge carrier;

Fig. 10 is a view similar to Fig. 9 after the cartridge carrier has been inserted in the inner shell and illustrating the manner of assembling the inner shell and outer shell;

Fig. 11 is a central vertical section of another form of lipstick holder embodying the present improvements;

Fig. 12 is a horizontal section taken on the line 12—12 of Fig. 11;

Fig. 13 is an elevation (similar to that of Fig. 9) showing the manner of inserting the cartridge carrier within the inner shell;

Fig. 14 is an exploded view of all parts of the second form of holder except for the absence of the cover;

Fig. 15 is an elevation of a modified form of combined inner shell and base, illustrating in particular a base with a high or long collar portion;

Fig. 16 is an elevation, partly broken away, of a complete lipstick holder embodying the combined inner shell and base of Fig. 15 and showing a short length cover seated upon the upper end of the collar portion; and

Fig. 17 is a horizontal section taken through the cover and base and showing diagrammatically the action of the spring fingers on the base which hold the cover in place thereon notwithstanding any warping or distortion of the cover in manufacture.

Reference will first be made to the embodiment shown in Figs. 1 to 10, wherein the parts are made partly of metal and partly of molded plastic material.

The lipstick holder, when assembled for use, includes an inner cylindrical shell A having a

bore A¹ serving as a guide for a carrier or cup B containing a lipstick cartridge C. The lower end of the inner shell is closed except for an octagonal opening A² which, as will later be described, is utilized in fastening the inner shell to the base. The inner shell is open at its upper end and provided with a pair of diametrically opposite vertical slots A¹⁰ which serve as guides for upper and lower pairs of pins B¹ and B² projecting laterally from the cartridge carrier B. The vertical slots A¹⁰ are constricted at their upper ends to form narrow passages or slits A¹¹ which permit the two sections of the inner shell to be sprung apart to receive the pins B¹ and B² of the cartridge carrier (see Fig. 9) and which, on the other hand, permit the two sections of the inner shell to be sprung together in assembling the inner shell within the outer shell (see Fig. 10).

An outer cylindrical shell D encircles the inner shell A and is formed with a pair of like helical grooves D³ and D⁴ to receive the diametrically opposed pairs of pins B¹ and B² of the cartridge carrier B. As usual, the grooves are open at the lower end and closed at the upper end of the shell D. This particular arrangement of two pairs of pins on the cartridge carrier operating in two helical grooves formed in the outer shell forms no part of the present invention, being the subject of a separate application for patent filed by me under date of November 17, 1945, as Serial No. 629,291, which has matured into Patent No. 2,469,631, issued May 10, 1949.

In their assembled relation, the inner shell A and outer shell D are held together in rotatable fashion by means of a flange A¹⁴ formed at the upper end of the inner shell and seated in an annular recess D¹ formed in the upper end of the outer shell (see Fig. 2).

In addition to the laterally projecting pins B¹ and B², the cartridge carrier or cup B is formed at its base with a pair of vertical diametrically opposed ribs B³ upon which the lipstick cartridge C is impaled and by which it is held against rotation with reference to the carrier when in use.

In assembling the parts, the cartridge carrier D is first inserted into the bore A¹ of the inner shell A, as illustrated in Fig. 9, and then the outer shell D slipped over the inner shell as illustrated in Fig. 10. When the outer shell reaches its seat on the base, with the carrier pins B¹ and B² entered into the lower open ends of the helical grooves D³ and D⁴ of the outer shell, the flange A¹⁴ of the inner shell will snap into the annular recess D¹ at the top of the outer shell, thus locking the parts together but still leaving them free to rotate one with reference to the other. To facilitate the assembly of the parts, as just described, the bottom of the outer shell D is bevelled as at D².

A cap or cover E completely encloses the outer shell D, being seated at its lower end upon the base (yet to be described) and held frictionally in place thereon. As previously noted, and as will be clear from the drawing, there is full clearance between the cover and the outer shell so that relative rotation between the outer shell and the inner shell is impossible when the cover is in place, thereby eliminating any danger of crushing the lipstick cartridge against the top of the cover by any rotation of the base with reference to the cover.

As thus far described, the parts are or may be of the usual or any approved construction, although as herein illustrated the cartridge carrier B, the outer shell D, and the cover E are made

of plastic material, preferably molded nylon which allows an extremely thin cross section but with sufficient strength for proper operation. A further advantage derived by the use of molded nylon is that the parts may be made of light weight and yet possess sufficient wearing qualities to withstand normal actuation.

Referring now to the base construction, which constitutes the main feature of the present invention, it is first pointed out that the base is made in two parts, one a solid metal part and the other a sheet metal part.

The solid metal part is in the form of an annular flat, relatively thick, disc A⁷ presenting at its upper side a cylindrical recess or well portion A⁶, from the bottom of which rises a centrally located cylindrical lug A¹², hollowed out to facilitate the swaging operation shortly to be described.

The sheet metal part is in the form of a cup A⁵ fitted snugly within the well A⁶ of the disc A⁷ and having a rim A⁴ which overhangs and lies flatly upon the upper face of the disc A⁷. Rising from the outer periphery of the rim A⁴ is a cylindrical collar A⁹ arranged in spaced relation to the inner shell A. The cup A⁵ is formed in its bottom with a centrally located octagonal opening A³ to align with the similar opening A² formed in the bottom of the inner shell A. When the parts are assembled, as shown in Fig. 5, the lug A¹² will project up through these openings A² and A³ preparatory to the swaging operation which is resorted to in locking the parts together as a unitary structure. The effect of the swaging operation is illustrated in Figs. 7 and 8, from which it will be noted that the lug A¹² has been peened over by a specially designed tool to produce a series of down-struck tongues A¹³ which effectively lock the parts together both in a rotational sense as well as in a longitudinal sense.

It will be noted, by reference to Fig. 2, that the collar A⁹ is spaced sufficiently from the inner shell A to accommodate the outer shell D, which rests at its lower end on the rim A⁴. Thus, the line of juncture between the lower end of the outer shell and the base will be concealed by the collar A⁹, which partially encloses the outer shell from its lower end up, giving a neat and attractive appearance to the finished article notwithstanding any crudeness in the fit between the outer shell and base.

As best shown in Figs. 4 and 5, the collar A⁹ is formed with three sheared-out spring fingers A⁸ located at 120° apart around the circumference of the collar and protruding beyond the outer face thereof to make frictional contact with the inner face of the cover E, which, it may be noted, rests at its lower end upon the upper face of the disc A⁷. These spring fingers A⁸ are thoroughly resilient and have a range of action corresponding to the tolerances allowed in the manufacture of the cover. That is to say, the spring fingers will be made to protrude far enough beyond the outer face of the collar A⁹ to accommodate covers of the largest, as well as the smallest, inside dimension, yielding more or less to conform to the actual inside dimension of the cover but always exerting enough friction to hold it in place while still permitting the base to turn freely or idly with reference to the cover. The spring fingers present sloping or rounded portions for contact with the lower edge of the cover as it is applied to the base.

What has just been said with reference to the action of the spring fingers A⁸ would apply even

assuming true concentricity of the cover, which seldom occurs in practice. Actually, a cover of a given diameter or a cover having a circumferential dimension which remains within the manufacturing tolerances, will warp into an elliptical or egg-shape at its lower end and exaggerate the condition under discussion. This is well portrayed in Fig. 17 which is in the nature of a diagram showing the action of the three spring fingers A⁸ in connection with a warped cover of elliptical shape at its lower end. As will be noted, notwithstanding the shape of the cover, the spring fingers will make yielding contact therewith, yielding different distances according to how close the inner face of the cover approaches the outer face of the collar A⁹. Taking into account the manufacturing tolerances, it is possible to calculate the maximum and minimum distortion which the cover may assume and therefore bend or form the spring fingers outwardly from the outer face of the collar to meet the maximum tolerance or deviation, whether it be on the plus or minus side.

While the invention does not exclude a greater number of spring fingers, it is pointed out that three such fingers, as herein shown, make the ideal arrangement, since they are all bound to function regardless of the size or shape of the cover (within the manufacturing tolerance of course).

Fig. 17 will also serve to emphasize the defect heretofore mentioned which arises from attempting to hold the cover in place by means of rigid or non-yielding friction surfaces. In other words, it is evident that in the case of such rigid surfaces an irregularly shaped cover could not be held in place at sufficient points to create the necessary friction.

While, as before stated, the cartridge carrier 40 B, the outer shell D, and the cover E are preferably made of molded nylon, the remaining parts, namely, the inner shell and the base, are made of metal. Thus, the inner shell A and the cup A⁵ with its rim A⁴ and collar A⁹, are 45 formed of drawn sheet metal but possessing the necessary degree of rigidity and flexibility at the proper points, while the disc A⁷ is of solid metal which is pressed into the required shape in conventional manner on standard types of screw 50 machines or headers. A simple adjustment of these machines can readily be effected to vary the over-all dimension of the disc A⁷ to cooperate with a plastic cap, such as shown, or a metal cap, such as hereinafter described, without having 55 to provide new tools and dies for each different size of cap. It is advantageous to make the inner shell and the base of three separate parts, as shown, since these parts can be fabricated separately and then assembled together as 60 a unitary structure without undue complexity of tools and dies and without undue waste of material and labor in the event of rejections due to faulty manufacture. If desired, the disc A⁷ could be made of sheet metal and thus of hollow form, 65 but it is preferred to make it of solid metal, as shown, not only because of manufacturing advantages, but also because of the added weight which it affords. This added weight is desirable to prevent top-heaviness when the holder is 70 placed in an upright position with the lipstick projected from the bore for use.

Reference will next be made to the second embodiment shown in Figs. 11 to 14, wherein all the parts are made of metal.

The inner shell F and the base comprising the

solid metal part F^2 and the sheet metal part F^1 are the same as in the first embodiment already described, except in the following particulars: In the present instance, the inner shell has a single guide slot F^5 for a single pin G^1 formed on the cartridge carrier G , said slot terminating at its upper end in a slit F^6 which permits the inner shell to be sprung out as shown in Fig. 13 for the insertion of the carrier. A bead F^4 , located slightly below the upper end of the shell F , replaces the flange A^{14} of the first embodiment and serves to provide for the necessary swivel connection between the inner and outer shells. The solid metal part F^2 of the base, although of the same thickness and form, is of slightly less diameter than the disc A^7 of the first embodiment, since the wall thickness of the cover J of this second embodiment is slightly less than the thickness of the cover E of the first embodiment.

The major difference between the two embodiments resides in the form of the outer shell which, in the present instance, is composed of an inner sleeve H and an outer sleeve I . The inner sleeve is formed with a full length slit H^1 for assembly purposes, with a single helical slot H^3 to cooperate with the carrier pin G^1 , and with a pair of notches H^4 and H^5 , one at each end. The outer sleeve I is open at its lower end, where it is formed with an inturned lug I^1 , and it is also open at its upper end where it is formed with a rolled-in flange I^2 .

In assembling the parts, the inner sleeve H of the outer shell is slipped over the inner shell F from the top, as permitted by the slit H^1 , until it comes to rest upon the base with its upper edge in engagement with the underside of the bead F^4 (see Fig. 11). During this operation, the sleeve H may be rotated with reference to the inner shell F until the lug G^1 of the cartridge carrier G registers with the helical slot H^3 . With the inner sleeve in place around the inner shell F , the outer sleeve I is next applied in similar fashion, being pushed all the way down over the assembly until it comes to rest on the base with its rolled-in flange I^2 overhanging and covering the upper end of the inner shell F . Once the outer sleeve I is in place, the lug I^1 near its lower end will snap into the notch H^4 formed in the lower end of the inner sleeve H and thus lock the parts together as one. In other words, the inner and outer sleeves H and I , in the assembled condition of the parts, will make up a composite outer shell similar in all respects to the one-piece outer shell D of the first embodiment. The notch H^5 in the upper end of the sleeve H will cooperate with the lug I^1 on the outer sleeve I in the same way as the notch H^4 if the sleeve H should be assembled upside down. Thus, by the use of the two notches H^4 and H^5 , the workman assembling the parts does not have to be concerned about which end of the sleeve H is slipped over the inner shell F .

The cap or cover J , previously identified, is applied in the same way as the cap or cover E of the first embodiment, resting at its lower edge upon the disc-like solid part F^2 of the base and being held in place thereon by the frictional engagement of the three spring fingers F^3 presented by the collar of the sheet metal part F^1 of the base.

In this second embodiment the lipstick cartridge K is held in place in the carrier G by means of an inwardly formed bead G^2 which embeds itself in the cartridge as it is pushed down into the carrier. It may be noted that this bead G^2 , as

75

well as the pin G^1 , are pressed from the sheet metal body which composes the carrier G .

Reference is now made to Fig. 15, which shows an all-metal lipstick holder such as that of the second embodiment just described, with this single difference, that the sheet metal part F^1 of the base is made with a higher or longer collar or sleeve F^7 which rises to a height approximately two-thirds of that of the holder to enclose and cover a corresponding extent of the outer shell from the base up. By making the sheet metal part of the base with such an extended collar or sleeve portion, a substantial surface is provided for instructions or advertising indicia, such as indicated in Fig. 15, and which is normally concealed when the cap or cover is in place. It will be noted that, notwithstanding the extended character of the collar F^7 , the three spring fingers F^3 will still function to make frictional contact with a full length cover when it is applied and seated on the base, as clearly illustrated in Fig. 15.

There remains to be described the modified form of lipstick holder shown in Fig. 16 which differs from the form shown in Fig. 15 primarily in the fact that the three spring fingers F^3 of the sheet metal part F^1 of the base, instead of being formed at the lower end of the collar F^7 , are formed at the upper end thereof to make frictional contact with a short length cover L . In this instance, the collar F^7 is also formed near its upper end and below the spring fingers F^3 with an annular shoulder F^8 to provide a seat for the lower end of the cover L . In providing the annular shoulder F^8 , the main body portion of the collar F^7 is spaced at a greater distance from the outer shell I than in the form shown in Fig. 15, and the fingers F^3 sheared out of a constricted portion at the top which is more closely spaced in relation to the outer shell I . This particular form of collar F^7 , of course, is not necessary since it could be made of smaller diameter and still be formed with the spring fingers F^3 and the underlying shoulder F^8 . Heretofore, in the case of a lipstick holder with a short length cap or cover, such cap or cover is held in place by frictional engagement with the outer shell of the holder, which means that the outer and inner shells of the holder can be rotated relatively to each other, even when the cover is in place, and thus allow the lipstick cartridge to be forced up against the cover and crushed. In other words, "free wheeling" in the case of short length covers, such as provided by the modified form of lipstick holder under discussion, has been unknown to the art. Perhaps another way of viewing the invention, in the modified form of Fig. 16, is to consider the collar F^7 of the base as a fixed or permanent cover for a substantial part of the holder and the cap L as a removable cover for the remaining part of the holder, it being understood that when the cap L is in place the outer shell of the holder is completely inaccessible and can partake of no rotation with respect to the inner shell to actuate the cartridge carrier, but that when the cap L is removed, the then exposed upper portion of the outer shell can be grasped for the actuation of the cartridge carrier by rotating the base, of which the collar F^7 forms a part, with reference to the outer shell.

In the accompanying drawings, the invention has been shown in different preferred forms, and by way of example, but obviously many variations and modifications may be made therein which will still be comprised within the spirit of the invention. It is to be understood, therefore, that

the invention is not limited to any specific form or embodiment except insofar as such limitations are specified in the appended claims.

Having thus described my invention, what I claim is:

1. A lipstick holder including, in combination, inner and outer shells rotatable with relation to each other and a cover, said inner shell at its lower end being provided with a flat annular outwardly extending rim, said rim having an annular wall depending from the inner perimeter thereof, and a shield having a lower collar affixed to said annular wall to rotate therewith, a flat annular ledge extending from the top of said collar and seated on said rim, and an upper collar rising from the outer perimeter of said ledge, the outer shell at its lower end being seated on the ledge between the inner shell and said upper collar, and the cover at its lower end surrounding and contacting the upper collar.

2. A lipstick holder including, in combination, inner and outer shells rotatable with relation to each other and a cover, said inner shell at its lower end being provided with a flat annular outwardly extending rim, said rim having an annular wall depending from the inner perimeter thereof, and a shield having a lower collar affixed to said annular wall to rotate therewith, a flat annular ledge extending from the top of said collar, and an upper collar rising from the outer perimeter of said ledge, the outer shell at its lower end being seated on the ledge between the inner shell and said upper collar, and the cover at its lower end surrounding and contacting the upper collar.

3. A lipstick holder including, in combination, inner and outer shells rotatable with relation to each other and a cover, said inner shell having a base comprising, first, a disk formed in its upper face with an annular depression in which the lower part of the inner shell is disposed and presenting an outwardly extending flat supporting surface upon which the cover is seated at its lower end and, second, a sheet metal shield presenting a flat annular rim resting upon the supporting surface of said disk and formed with two collars, one depending from the inner perimeter of the rim and located between the inner shell and the adjoining wall of the annular depression formed in the disk, and the other rising from the outer perimeter of the rim and located between the outer shell and the cover and formed for frictional contact with the inner surface of the cover to hold the latter removably in place.

4. A lipstick holder including, in combination, inner and outer shells rotatable with relation to each other and a cover, said inner shell at its lower end being provided with a flat annular outwardly extending rim, said rim having an annular wall depending from a perimeter thereof, and a

shield having a lower collar affixed to said annular wall to rotate therewith, a flat annular ledge extending from the top of said collar and seated on said rim, and an upper collar rising from the perimeter of said ledge, the outer shell at its lower end being disposed between the inner shell and said upper collar, and the cover at its lower end surrounding and contacting the upper collar.

5. A lipstick holder including, in combination, inner and outer shells rotatable with relation to each other and a cover, said inner shell having two base members, one base member presenting a flat annular outwardly extending rim with an annular wall depending from a perimeter thereof, and the other base member presenting a lower collar affixed to said annular wall to rotate therewith, a flat annular ledge extending from the top of said lower collar, and an upper collar rising from the perimeter of said ledge in spaced relation to the inner shell, the outer shell at its lower end being disposed between the inner shell and said upper collar, and the cover at its lower end surrounding and contacting said upper collar.

6. A lipstick holder according to claim 5, wherein the upper collar encloses the major portion of the outer shell, and wherein the cover is of full length and completely encloses the upper collar.

7. A lipstick holder according to claim 5, wherein the upper collar encloses the major portion of the outer shell, and wherein the cover is of short length and only partially encloses the upper collar.

8. A lipstick holder according to claim 7, wherein the short length cover is seated at its lower end upon an annular shoulder formed on the upper collar below its upper end.

HARRY BRODER.
